DOOR LOCK

Robert Buchanan McFarlane, Toronto, Ontario,
Canada

Application August 14, 1936, Serial No. 95,977

13 Claims. (Cl. 70—147)

My invention relates to improvements in door locks and is particularly designed for use on automobile doors. The object of my invention is to provide a lock mechanism wherein the usual actuating handle is eliminated, the lock being operated by manual movement of the key receiving portion of the lock inwardly towards the door.

A further object of my invention is to utilize such inward movement of the key receiving portion of the lock to move the lock bolt into the disengaged or unlocked position and at the same time to compress a spring which swings the door open a slight degree as soon as the bolt is released.

15. A further object of my invention is to furnish a movable plate, which when in the locked position, covers the bolt actuating portion of the lock so that the bolt would remain in the locked position in spite of any attempts of thieves to 20 drive the locked key receiving portion of the lock inwardly.

With these and other objects in view, my invention consists of a lock constructed and arranged all as hereinafter more particularly described, and illustrated in the accompanying drawings in which—

Fig. 1 is a horizontal cross-sectional view through the outer edge portion of an automobile door showing my lock contained therein.

30. Fig. 2 is a similar view to Fig. 1, being partly in section and also showing the bolt in the withdrawn position.

Fig. 3 is a front elevational view of the fragmentary portion of the door containing the lock and also a fragmentary portion of the door jamb.

Fig. 4 is a side elevational view of the fragmentary portion of the door containing the lock.

Fig. 5 is a front elevational view of my lock 40 apart from the door.

Fig. 6 is a horizontal cross-sectional view through the door jamb, being taken through a line on the same plane as the line 6—6, Fig. 4.

Fig. 7 is also a horizontal cross-sectional view 45 through the door jamb being taken through a line in the same plane as the line 7—7, Fig. 4.

Fig. 8 is a horizontal cross-sectional view 50 through the lock being taken through the line 8—8, Fig. 5.

Fig. 9 is a similar view to Fig. 8, the bolt being shown in the withdrawn position.

Fig. 10 is a side elevational view of my lock.

Fig. 11 is a vertical sectional view taken 55 through the line 11—11, Fig. 10.

Fig. 12 is a similar view to Fig. 11, the bolt being shown in the withdrawn position.

Fig. 13 is a horizontal cross-sectional view through the lock, being taken through the line 13—13, Fig. 11.

Fig. 14 is a perspective view, partly in section, of the key receiving portion of my lock, showing the latch therein in the locked position, and

Fig. 15 is a similar view to Fig. 14, showing the latch in the unlocked position.

Like characters of reference indicate corresponding parts in the different views of the drawings.

My lock comprises a base plate 1 upon which the various lock elements are mounted. This plate is secured against the inner side of the door 2 in any suitable manner, the bolt 3 and the lug 4 protruding through the orifices in the edge of the door. The bolt 3 slides upon the face of the plate 1 and is supported at one end by a U-shaped strap 5 which is secured to the plate, and at the other end protrudes through an orifice 6 in the turned-up edge 7 of the plate 1. The door jamb 8 is formed with a recess 9 for the reception of the bolt end as illustrated in Fig. 6. The end of the bolt 3 has an inclined face so that it moves inwardly as the door is closed, following standard practice.

Upon reference to Figs. 8 and 9, it will be seen that the bolt 3 is formed with a transverse orifice 10 extending therethrough, in the vicinity of its protruding end. The portion 11 of the bolt at the inner end of the orifice 10 is raised in height and the face 12 of the orifice curves upwardly to such portion.

The bolt is normally retained in the protruding position by a spring, as shall be hereinafter explained, and to draw or move the bolt inwardly I furnish a plate 13 which is movable towards the bolt 3. The inner face of the plate 13 carries a wedge member 14, the inclined face 15 of which 35 engages the curved face 12 of the orifice 10 in the bolt. As the plate 13 is moved towards the bolt, the wedge 14 enters the orifice 10 and through the engagement of the respective faces 15 and 12 the bolt is slid inwardly from the position shown in Fig. 8 to the position shown in Fig. 9.

In order to return the plate 13 to its initial position and permit the bolt to again protrude, the plate 13 is formed with the lug 4 which protrudes from the edge of the door. When the bolt is in the withdrawn position as illustrated in Figs. 2 and 9, the plate 13 has moved horizontally into the position shown in dotted lines in Fig. 4. To return the bolt 3 to the protruding position, 50

the plate 13 and lug 4 have to be moved to the position shown in full lines in Fig. 4. In accomplishing this, I provide the construction as shown in Fig. 7, wherein it will be seen that the 5 door jamb 8 is formed with a long transverse recess 16 having a slot 17 in the bottom thereof through which a lug 18 protrudes. The lug is carried upon a movable cap 19 which is movable along the length of the slot 17 against a spring 20. 10 When the door is closed with the bolt 3 withdrawn, the lug 4 comes into engagement with the spring held lug 18 in the jamb, and the strength of the spring 20 is sufficient to retain the lug 18 substantially in the position illustrated in Fig. 7 15 wherein it must, of course, push the lug 4 from the position shown in dotted lines in Fig. 4 to the position shown in full lines, whereby the plate 13 and wedge 14 are moved away from the bolt, and the bolt permitted to move outwardly and 20 into the recess 9 in the door jamb.

Superposed in spaced relation to the plate 13, I furnish a second rectangular plate 21 which is secured to the plate 13 by a pair of corner bolts 122 passing through the plates and having spacing 25 washers carried thereon. The plate 21 has a cylinder 22 centrally mounted on its outer face and surrounding an orifice 23 in the plate. The cylinder 22 carries a lock 24 in its outer end, and through which protrudes a lock operated rollback 30 25, movable into the positions illustrated in Figs. 14 and 15 through the use of a withdrawable key 26.

The plates 13 and 21 are formed with aligned orifices in the vicinity of their ends for the 35 reception of guide posts 27 which extend upwardly from the base plate 1. The upper ends of the posts are contained within orifices in a U-shaped strap 28 which is secured to the base plate 1 and extends over the plates 13 and 21. 40 The strap is formed with a central orifice 29 through which the cylinder 22 protrudes. The plates 13 and 21 slide upon the posts 27, and to obviate binding, the plate 13 carries a pair of sleeves 30 surrounding the posts. The upper 45 ends of the sleeves 30 extend to the bottom face of the plate 21.

In order to provide a synchronization between the outward movement of the bolt 3 and the movement of the plate 13, I furnish a link 31 which is pivotally connected at one end to the 50 side of the bolt and at the other end to a lug 32 in the bottom face of the plate 13. As the plate 13 moves outwardly the pull of the link retracts the bolt 3. As the cylinder carrying plate 21 is secured to the plate 13, it will be seen that when 55 the cylinder, which is designed to protrude from the face of the door, is pushed inwardly, that the bolt 3 will be withdrawn and permit the door to open. As the plate 13 moves inwardly under 60 pressure exerted against the cylinder, the lug 4 also moves inwardly and through its engagement with the lug 18 compresses the spring 20. When 65 the plate 13 has been pushed inwardly to fully retract the bolt 3 and disengage it from the orifice 9, the bolt and wedge 14 are in relative engagement as shown in Figure 9, with the spring 20 fully compressed and tending to move the lug 4 outwardly. After the cylinder 22, plate 13 and lug 4 have been pushed inwardly, the operator 70 removes his inward hand pressure against the cylinder 22, at which instant the compressed spring 20 pushing against the lug 4 kicks the door open several inches. In other words, as the door is freely swung, the outward movement of 75 the lug 18 under the pressure of the spring 20

moves the door sufficiently to prevent the bolt re-entering the orifice 9, and further expansion of the spring 20 continues the door opening movement. The lug 4 through its engagement with the spring actuated lug 18 has a tendency to 5 move across the lock and reproject the latch 3, but the initial slight movement of the door is sufficient to move the point of the latch out of register with the orifice 9.

In order to lock the door against unauthorized 10 opening, I furnish a pin 33 which extends from the base plate 1 through the orifice 10 in the bolt 3 and also through an orifice 34 in the wedge 14 and its plate 13. The top of the pin 33 is substantially flush with the top of the plate 13 15 when the bolt is out and the lock in the position illustrated in Fig. 8. Upon the top of the plate 13 I provide an intermediate plate 35 which is swingable about one of the posts 27 and is so designed that in one position its curved end 20 36 lies alongside the top of the pin 33 and orifice 34, as illustrated in Fig. 12; and in another position covers the top of the pin 33 and orifice 34, as illustrated in Fig. 11. When the plate 35 is in the position illustrated in Fig. 11, it, through its 25 engagement with the top of the pin 33, retains the plate 13 against downward movement, thus locking the bolt in the protruding position.

The plate 35 can be swung into the unlocked position as illustrated in Fig. 12 either by means 30 of the key 26 or the cam plate 37. The cam plate is of substantially triangular shape and swingably mounted in the vicinity of one apex upon the other post 27. The plate is formed with a lug 38 which lies alongside the lug 4 and by means 35 of which the plate is manually swung into either of the two positions illustrated in Figs. 11 and 12. One edge of the cam plate engages the end 36 of the plate 35 to move it to unlocking position 40 shown in Fig. 12, whereby the door can be opened through pressing the cylinder 22 inwardly. As the cylinder 22 moves inwardly and depresses the plate, the end of the pin 33 becomes contained in the inner end of the cylinder as illustrated in Fig. 9.

If the door is locked, that is with the locking plate 35 in the position shown in Fig. 11 and it is desired to open the door, the key 26 is inserted in the lock and turned. The turning of the key swings the rollback 25 from the position shown 50 in Fig. 14 to the position shown in Fig. 15, and as such rollback 25 extends downwardly to a sufficient extent to engage the edge 39 of the end 36 of the plate 35 as illustrated in Fig. 10, its movement from the position illustrated in Fig. 14 to the position illustrated in Fig. 15 will swing the plate 35 into the position illustrated in Fig. 12 whereby the cylinder 22 may be pressed inwardly and the door opened. The orifice 44 in the plate 35 freely receives the arm 42 and is positioned very close to the post 27 about which the plate is swung, so that movement of the plate 35 from the position shown in Figure 11 to the position shown in Figure 12 causes very little resultant movement of the rod 40.

As it is desirable to so construct the lock that it will normally be locked against opening except with the use of the key, I provide a resilient means for moving the plate 35 into the position shown in Fig. 11 as long as the cam plate 37 is 70 left in the position illustrated in this figure. This means comprises a rod 40 slidably mounted upon a pair of blocks 41 carried upon the base plate 1. One end of the rod 40 supports an upwardly sloped arm 42 which freely protrudes through 75

orifices 43 in the plates 13 and 21, and also through an orifice 44 in the locking plate 35. The rod 40 is encircled by a spiral spring 45 which bears at one end against one of the blocks 41, and at the other against the collar 46 secured to the rod. The spring 45 is normally under compression and tends to move the arm 42 in the direction indicated by the arrow in Fig. 13. As the arm 42 bears against the side of the orifice 44 in the plate 35, it tends to resiliently retain the plate 35 in the position illustrated in Fig. 11. The other end of the rod 40 is connected to a cross bar 47 which is in turn connected to the inner end of the bolt 3 so that the tension on the spring 45 also tends to retain the bolt in the protruding position.

48 is a strap having a slot 49 therein through which the connecting pin 50 between the cross bar 47 and the bolt 3 passes. The other end of the strap 48 is connected to some suitable handle in the interior of the car so that when the handle is pulled the corresponding movement of the strap 48 will pull the bolt 3 to unlock the door from the inside of the car. When the bolt 3 is retracted through moving the lock 22 inwardly, the pin 50 slides along the slot 49 so that the handle inside the car is not moved. Upon reference to Figs. 1, 2, and 3, it will be seen that I form the outer face of the door with a recess 51 in which the outer end of the cylinder 22 is contained so that it does not protrude from the door. To retain the plate 13 in its inward or lock unlatched position I furnish a spring held ball stop 52 mounted on the side of the strap 28 and which engages the edge of the plate and retains it against free movement until the lock is again actuated. The ball stop 52 is only provided to retain the plate 13 against rattling movement, and is not sufficiently strong to interfere with the normal outward movement of the plate 13 when the door is being closed with the lugs 4 and 18 engaging one another. A spring ball stop 53 is also provided in the face of the plate 13 to engage either of two recesses 54 in the abutting face of the cam plate 37 when it is in either of the adjusted positions.

From the foregoing description it will be apparent that I have devised a simple and yet very efficient door lock, which although applicable to any type of door is more particularly designed for automobile doors, in that the provision of my lock obviates the necessity of providing the usual door handles which mar the streamlined appearance of modern cars and also which have caused serious injury in accidents where pedestrians are involved, and although I have shown a particular embodiment of my invention, it is to be understood that I can make such changes and alterations as I may from time to time deem necessary, without departing from the spirit of my invention as set forth in the appended claims.

What I claim as my invention is:

- In a door lock, a slidable bolt, a bolt retracting element movable inwardly from the face of the door to retract the bolt, and resilient door opening means supported by the door jamb and against which the bolt retracting element presses when moved inwardly to retract the bolt.
- In a door lock, a slidable bolt, a wedge element movable inwardly to engage and retract the bolt, a lug protruding from the wedge element through the side of the door, and resilient door opening means supported by the door jamb and against which the lug presses when the wedge element is moved inwardly to retract the bolt.

3. In a door lock, a slidable bolt, a bolt actuating wedge element movable inwardly from the face of the door to retract the bolt, and resilient door opening means supported by the door jamb and against which the actuating element presses when moved inwardly to retract the bolt. 5

4. In a door lock, a slidable bolt, a bolt actuating element movable inwardly towards the inner face of the door to retract the bolt, a stationary element positioned adjacently to the movable element, and a bolt locking member carried upon the bolt actuating element and adapted in one position to engage the stationary element and retain the movable member against bolt reTRACTING movement. 15

5. In a door lock, a slidable bolt, a bolt actuating element movable inwardly towards the inner face of the door to retract the bolt, a stationary element positioned adjacently to the movable element, a bolt locking member carried upon the bolt actuating movable element and adapted in one position to engage the stationary element and retain the movable element against bolt actuating movement, and key operated means to engage and actuate the bolt locking 20 member to move it out of engagement with the stationary element. 25

6. In a door and jamb, a lock mounted on the door, a slidable bolt incorporated in the lock and engaging the door jamb, a bolt actuating member 30 protruding from the door, and means supported by the door jamb and engaging and moving the bolt actuating member to move the bolt towards the jamb.

7. In a door and jamb, a lock mounted on the door, a slidable bolt incorporated in the lock and engaging the door jamb, a bolt actuating member protruding from the door, and resiliently movable means supported by the door jamb and engaging and moving the bolt actuating member 35 to move the bolt towards the jamb. 40

8. In a door and jamb, a lock mounted on the door, a slidable bolt incorporated in the lock and engaging the door jamb, a bolt actuating member protruding from the door and movable 45 towards the bolt, and means supported by the door jamb and resiliently movable across the jamb, said means engaging and moving the bolt actuating member during the closing of the door.

9. In a door and jamb, a lock mounted on the door, a slidable bolt incorporated in the lock and engaging the door jamb, a bolt actuating member protruding from the door and movable towards the bolt, a wedge movable in conjunction with the bolt actuating member and engaging and sliding the bolt, and means supported by the door jamb and resiliently movable across the jamb, said means engaging and moving the bolt actuating member during the closing of the door. 55 60

10. In a door and jamb, a lock mounted on the door, a slidable bolt incorporated in the lock and engaging the door jamb, a bolt actuating member protruding from the door and movable towards the bolt, a wedge carried by the bolt actuating member and engaging and sliding the bolt, a lug protruding from the door jamb and movable thereacross, a spring normally retaining the lug against movement, said lug engaging and moving the protruding portion of the bolt actuating member during the closing of the door. 65 70

11. In a door lock, a key receiving lock portion adapted slidably to protrude through the outside face of a door, a bolt slidably positioned rearwardly of the key receiving lock portion and 75

adapted to engage the door jamb, a wedge member movable inwardly in conjunction with the key receiving lock portion and adapted to engage and slide the bolt into the retracted position, a movable locking plate adapted to be interposed at will between the key receiving lock portion and the wedge member to retain such key receiving lock portion against inward movement, and a rollback movable under actuation of the key to engage and move the locking plate.

12. In a door lock, a key receiving lock portion adapted slidably to protrude through the outside face of a door, a bolt slidably positioned rearwardly of the key receiving lock portion and adapted to engage the door jamb, a wedge member movable inwardly in conjunction with the key receiving lock portion and adapted to engage and slide the bolt into the retracted position, a movable locking plate adapted to be interposed at will between the key receiving lock portion and the wedge member to retain such key receiving lock portion against inward movement, a rollback movable under actuation of the key to engage and move the locking plate, and a cam mem-

ber manually movable from the side edge of the door and also engaging and moving the locking plate.

13. In a door lock, a key receiving lock portion adapted slidably to protrude through the outside face of a door, a bolt slidably positioned rearwardly of the key receiving lock portion and adapted to engage the door jamb, a wedge member movable inwardly in conjunction with the key receiving lock portion and adapted to engage and slide the bolt into the retracted position, a movable locking plate adapted to be interposed at will between the key receiving lock portion and the wedge member to retain such key receiving lock portion against inward movement, a rollback movable under actuation of the key to engage and move the locking plate, a cam member manually movable from the side edge of the door and also engaging and moving the locking plate, and a spring tending to retain the bolt in the protruding position and the locking plate in the interposed position between the key receiving lock portion and the wedge member.

ROBERT BUCHANAN McFARLANE.
